UNITED STATES PATENT OFFICE

CHARLES L. MOHR, OF WILMETTE, ILLINOIS

SLUG PROFILING MACHINE

Application filed October 13, 1930. Serial No. 488,389.

This invention relates to improvements in means and methods for producing type bars of peculiar and novel form and has special reference to a mechanism for removing parts of type slugs such as are produced on what is known as a Ludlow typograph machine. Such slugs usually have the type faces of greater height than the slug bar upon which they are formed, and by means of this present invention, the overhanging parts can be easily and readily trimmed down or removed. Sometimes it is desired to produce a printed line of this character with a more or less heavy printed line or line of printing running through the letters from end to end of the line. In such a case, two of the type bars are taken, the top portions of letters are removed on one bar, and the bottom portions are removed on another bar and then a rule or line of type is placed between these two bars when they are assembled in a type form.

A further feature is that the mechanism embodying my invention can as readily be used to cut out tops of type bars for any purpose desired, the vise which holds the type bar to be operated upon being capable of being set in different positions in relation to the cutter for holding the type bar in different positions relative to the cutter.

The invention contemplates the production of the type bars in the regular manner and then their cutting away or profiling to produce the desired novel results.

The invention will be more readily understood by reference to the accompanying drawings forming part of this specification and in which:—

Fig. 1 is a fragmentary top plan view of a novel machine by which the method of producing novel printing forms may be best practiced;

Fig. 2 is an end elevation of the machine shown in Fig. 1, when viewed in the direction of the arrow on Fig. 1;

Fig. 3 is a vertical sectional view substantially on the line 3—3 of Fig. 1;

Fig. 4 is a sectional view similar to Fig. 3 but showing parts in different relative positions;

Fig. 5 is a sectional view on the line 5—5 of Fig. 4;

Fig. 6 is a fragmentary vertical section on the line 6—6 of Fig. 5;

Fig. 7 is a fragmentary substantially horizontal section on the line 7—7 of Fig. 3;

Fig. 8 is a fragmentary vertical section on the line 8—8 of Fig. 3;

Fig. 9 is a fragmentary vertical section on the line 9—9 of Fig. 8;

Fig. 10 is a fragmentary horizontal section on the line 10—10 of Fig. 1;

Fig. 11 is a fragmentary horizontal section on the line 11—11 of Fig. 2;

Fig. 12 is a fragmentary vertical section on the line 12—12 of Fig. 1;

Fig. 13 is a fragmentary top plan view of one form of type bar which is adapted to be changed by the use of the machine;

Fig. 14 is a fragmentary side view of the type bar shown in Fig. 13 and showing the result of the change effected by the machine;

Fig. 15 is a vertical section on the line 15—15 of Fig. 14;

Fig. 16 is a top plan view of another form of type bar adapted to be changed by the use of the machine;

Fig. 17 is an end view of the type bar shown in Fig. 16;

Fig. 18 is a top plan view of the bar shown in Fig. 16 in combination with a rule, the bar shown after being changed by the use of the machine;

Fig. 19 is a vertical section on the line 19—19 of Fig. 18;

Fig. 20 is a top plan view of two associated type bars shown in full lines before change and dotted lines after change;

Fig. 21 is a view similar to Fig. 20 but showing the two type bars as they would be set for printing;

Fig. 22 is a plan view showing the result of printing by means of the type bars shown in Fig. 21;

Fig. 23 is a top plan view of another form of type bar shown associated with a rule and as having been changed by use of the machine;

Fig. 24 is a vertical section on the line 24—24 of Fig. 23; and

Fig. 25 is a plan view showing the printed result of the bar shown in Fig. 23.

In order that a clear idea of the invention may be quickly attained, it has been thought best to describe the product first.

In said drawings, Figs. 16 to 19, inclusive, particularly illustrate a printing member 30 in the form of a slug having a very wide printing face 31 cast on or in conjunction with a relatively narrow bar 32, the type faces 31 overhanging the bar 32 on both sides. The machine illustrated is capable of being operated to trim off one edge of the type face, as illustrated by the dotted lines 33, Fig. 16, for the purpose of making peculiar or novel display advertisements; in this instance, to permit the type bar 30 to be associated with a type rule 34 when set in a form for use.

As usually produced, such wide face type faces have an edge portion 37 which extends above and below the actual type faces. It is desirable, in some instances, to set a rule 38 close to either the top or the bottom of the type faces. For this purpose, the overhang is trimmed off by means of the machine and then a rule 38 can be set in the type form close to the printing faces. The printed result is shown in Fig. 25 when the heavy printed line 40 is shown close to the bottom of the letters 41.

It will be obvious that many other combinations can be produced, such, for instance, as a heavy line or a line of type inserted through the middle of a line of letters by trimming off the bottom parts of the type faces of one slug and the top parts of the type faces of a similar or duplicate slug, and placing a rule between these two parts when they are assembled in a printing form.

Another very desirable result to be produced is the close association of type bars which have display letters of varying heights. Such a use is illustrated in Figs. 21 to 22, inclusive.

In this instance, two type bars, such as 42 and 43, are produced. These bars have, as usual, the overhanging blank edge portions 37 and they have some letter faces which are wider than others. When it is desired to closely associate these type bars as indicated in Figs. 21 and 22, the overhanging edge portions can be trimmed away, as indicated by the dotted lines 44, Fig. 20 to provide notches, etc., to receive the overhanging wider letters. Fig. 22 shows the printed result of such cutting and close associating of the type bars 42 and 43.

In Figs. 13 to 15, another important use of the machine is illustrated.

Some type bars 45 or keyboard slug machine printing slug have blank spaces 46 between type faces. These blank spaces, as formed, are but slightly below the level of the printing faces and, in some cases, in use such blanks may smudge the printed page. This

necessitates the cutting down or notching of the upper edges of such slugs. This cutting down is shown by the full line 47, Figs. 15 and 16, the original top being shown by the dotted line 48, Fig. 14.

Another important use is to cut down or notch the tops of type slugs to permit the overhanging tops of other machine cast slugs to project over the slug. For instance, an adjacent slug might have a part adapted to project over and rest upon the surface 47.

The machine for producing these and other novel or desired results as illustrated in the drawings, consists of a frame having a base 50 and various upstanding brackets, lugs, etc., which support and carry the several working parts of the machine. The machine may be provided with yielding feet 51, if desired.

The working parts of the machine consist mainly of a vise mechanism 52 and a co-operating rotary cutter 53. The cutter 53 is preferably in the form of a circular milling cutter and is rigidly mounted on a horizontal rotatable shaft 54. The shaft is carried in upper ends of bearing standards 55 which may either be integral with the base 50 or secured thereto.

Between the standards, the shaft 54 carries a belt pulley 56 which operatively connects the pulley with an electric motor 57 carried on a suitable extension 58 of the machine base 50.

The vise mechanism 52 has a frame 59 formed at its lower part to provide two spaced apart bearings 60 which are mounted on a horizontal shaft 61. The shaft 61 is a guide rod and is fixed at its ends in perforated projections 62 projecting up from the base 50. The vise frame is adapted to slide back and forth horizontally on the shaft 61 and to swing up and down on same to cause the cutter 53 to operate on the article held in the vise.

The vise frame 59 has end plates or arms 63. The vise for holding the slugs for presentation to the cutter 53 consists of a relatively fixed jaw 64 and a relatively movable jaw 65.

The relatively fixed vise jaw 64 is formed on a plate member 66 which is pivotally mounted at its upper end on a horizontal shaft 67, which is rigidly mounted on the upper parts of the end plates 63 of the vise frame 59, as best shown in Fig. 5. The frame 66 is capable of being swung up and down on the shaft 67, the two limiting positions being indicated in Fig. 6, and also indicated, in reference to the cutter 53, in dotted lines in Figs. 3 and 4.

The plate 66 depends between the frame ends 63 and its middle lower portion is cut away, as best shown in Fig. 6 at 68, to provide projections 69 between which a vise plate member 70 is mounted on horizontal pivot pins 71 to swing. The movable vise jaw 65 is secured

upon the upper end of the vise plate 70 and is adapted to be swung in and out to clamp and loosen a type slug by a hand screw 72 secured in a threaded opening in the plate 66, and having a shoulder 73 for contact with the outer end of a hollow projection 74 on the outer side of the plate 68. Within the hollow outer end of a hollow projection 74 on the screw 72 to normally hold the two vise jaws separated to the limit permitted by the screw 72. The vise as thus described is arranged parallel with the axis of rotation of the cutter 53; it is movable as a whole horizontally past the cutter; the jaws are capable of being set substantially vertically or horizontally or in any intermediary position as necessity demands, in relation to the cutter by swinging movement on the shaft 67; and the vise mechanism can be swung, as a whole, from and toward the cutter on the lower shaft 54.

The vise frame 58 is provided at its lower edge with a rigid projection 76 for contact with the base 50 to limit the downward swinging movement of the frame.

As shown, in Fig. 3, the vise is shown as set to present the overhanging edge portion 37 of a type slug 30 to the cutter 53 to cut off more or less of said edge, as shown in Figs. 16 to 18.

For this setting, the lower part of the vise is swung inwardly on the shaft 67 to hold the type slug in substantially vertical position, as shown in full lines in Fig. 3. The vise is retained in such position by means of a clamping screw 77 carried in a radial threaded opening provided in boss 78, projecting outwardly from the lower end of the frame 66 and adapted to be screwed in to engage the outer edge 79 of one of the end plates 63 of the vise frame 59 and hold the frame 66 in relation to the frame 59. An adjustable stop 80 is arranged in the main vise frame 59. This stop is in the form of a screw mounted in a threaded opening provided in the vise frame 59 and adapted to project toward the frame 66. The screw 80 is held in its adjusted position by a jamb nut 81. This adjustment is for the purpose of presenting the type slug to the cutter in such a relation that the slug part 37 of the slug 30 is presented tangentially to the cutter, as best shown in dotted lines in Fig. 3.

After the screw stop 80 has been once set, it does not need to be disturbed. When a slug is clamped in the vise jaws by the clamping screw 72 and the frame 66 is set against the stop 80 and clamped in such position by the clamping screw 77, the vise frame 51 is then swung over toward the cutter, as shown in dotted lines in Fig. 3, to cut off the overhanging edge of the type faces. The engagement of the cutter teeth with the overhanging edge of the slug is controlled to prevent a too great engagement by means of a readily adjustable stop mechanism. This stop mechanism consists of a horizontal stop bar 82 arranged on the inner side of the vise

frame 59 and adjustable in relation to said frame to two positions, one for retaining the vise in a desired relation to the cutter for trimming off the edges of overhanging type faces, and the other for cutting down into the tops of type bars.

The stop bar 82 is mounted in notches 83 provided in the inner edges of the ends 63 of the frame 59 and is adapted to be yieldingly held inwardly by tension springs 84, each attached at one end to the ends 63 and at their other ends to the bar 82. The stop bar 82 is adapted to be set in its two positions by means of cam levers 85 at one end of the frame 63 and 86 at the opposite end of said frame. These levers are pivotally mounted on horizontal pivot screws 87 for the lever 85, and 88 for the lever 86. These pivots are arranged close to the stop bar 82. The pivoted ends of the cam levers are provided with two flat surfaces 89 and 90 for engagement with the stop bar 82 to set the bar in the two positions.

The levers 86 and 88 are adapted to be swung on their pivots from one limiting position to the other, by the swinging of the frame 64 from one of its limiting positions to the other. When the frame 64 is swung down for cutting the overhanging type faces, the stop bar 82 is pushed out to its limit and when the frame 64 is swung up for cutting the tops of the type bars, the stop bar 82 is drawn into the notches 83. This is accomplished by cross-head blocks 91 fixed on the ends of the frame 66 by screws 92, the free ends 93 of the cam levers being bifurcated or slotted to straddle the cross-heads. This sliding connection with the cam levers is provided to allow for the radial movement of the connection with the frame 66 and the levers on account of the different centers upon which they swing.

To limit the upward swinging of the frame 66 for setting the vise radial to the cutter 53, an adjustable stop 94 is arranged on one of the ends 63 of the frame 59 in the path of a projection 95 on one end of the frame 66. This stop 95 consists of a screw mounted in a threaded opening provided in a projection 96 on the inner side of one of the ends 63 of the frame 59, and adapted to be secured in its adjustable position by a set screw 97. When the frame 66 is swung up against the stop 95, it is secured in such position by the clamping screw 77 which is forced in against the edge 98 of the adjacent end 63 of the frame 59. Said edge 98 is preferably curved in a radius struck from the center of the shaft 67 upon which the frame 66 swings so that the inner end of the clamping screw will not touch the end 63 as the frame 66 is swung up and down. The upper position of the frame is shown in dotted lines in Fig. 6 and in full lines and dotted lines in Fig. 4. As well illustrated in Fig. 4, when the frame 66 is

swung up, the slug which is carried by the vise will be presented radially to the cutter 53 for the purpose of cutting notches in its upper edge, as illustrated in Figs. 13 and 14. 5 Besides the limiting of the swinging of the frame 66 to set the vise in the proper relation to the cutter for performing the two kinds of operations, it is necessary to limit the inward swinging of the vise mechanism to prevent 10 the cutter taking too deep a cut. For this purpose and for readily allowing the vise mechanism to be adjusted to carry the slug forward toward the cutter for successive cuts, a readily adjustable stop mechanism is provided. 15

This stop mechanism consists of a stop bar 99 mounted in a horizontal position transversely of the machine and provided with a longitudinally adjustable end 100 for contact 20 with the longitudinal stop bar 82 carried by the vise frame 59.

The stop bar 99 is mounted in bearings 101 and 102 for horizontal movement toward and from the stop bar 82. The bar 99 is yieldingly 25 held rearwardly by a coiled spring 103 mounted within the bearing 102 and arranged between the head 104 of a screw 105 received in a threaded opening in the adjacent end 106 of the bar 99, and a shoulder 107 at the inner 30 end of the bearing 102. The adjustable end 100 of the bar consists of a screw adapted to be received in a threaded opening provided in the adjacent end 108 of the bar 99 and held in its adjusted position by a jamb nut 109.

35 The bar 99 is adapted to be forced toward the stop bar 82 against the action of the spring 103 by a vertical hand screw 110. This screw has a knurled handle 111 which stands at the top of the machine in a position to be readily 40 grasped by the operator. The screw 110 is mounted in a threaded opening in a boss 112 on the frame. The lower end 113 of the screw 110 is rounded for contact with a flat arm 114. The arm 114 is fixed on the adjacent end of a 45 rock shaft 115 which is mounted horizontally in the frame of the machine below and at right angles to the stop bar 99. The end of the shaft 115 opposite to the lever 114 carries a rigid slotted lever arm 116 which projects alongside of the stop 99. A pin 117 is fixed 50 in the stop bar 99 and projects into the slot 118 of the lever 116. The arrangement is such that when the screw 110 is screwed down, the stop bar 99 is adjusted toward the stop bar 82.

55 Before swinging the vise to present a slug to the cutter, the screw 110 is preferably screwed down to force the stop bar 99 out far enough to cause the cutter to clear the extending shoulder of the face of the slug. Then, by backing off the screw 110, the vise with the slug can be gradually moved into contact with the cutter until a deep enough cut is attained, then the vise mechanism is 60 moved endwise on the guide shaft 46 to com-

plete the cut, either the whole length of the slug or less, as may be desired.

As the cutter preferably operates at high speed, it is preferable to provide a guard to prevent the chips being thrown about and to 70 guide them down into a receptacle. It is advisable to provide a guide chute for the chips below the cutter which substantially maintains contact with the longitudinal stop bar 82, but as this bar moves in and out in relation to the frames 66 and 59 and in relation to the frame of the machine, it is necessary to provide a guide chute for the chips which 75 will follow this bar.

The chip guard and guide consists of an 80 open-topped chute 119 arranged beneath the cutter 53. The chute has a forward wall 120 which is rearwardly and downwardly inclined, the upper edge portion of which rests against the forward or inner face of the stop 85 bar. The chute also has a rear wall 121 which is curved to one side to cause the chips to be thrown out to one side or end of the machine. The chip chute 119 is secured to and carried by a flat bar or plate 122 which is 90 arranged in vertical position and adapted to move back and forth transversely of the machine. This plate is mounted for its movement on headed screws, the plate being provided with horizontal slots 123 to receive the 95 screws beneath the heads. The plate is yieldingly held with the chute in contact with the stop bar 82 by a light tension spring 124.

The plate 122 has an upstanding projection 125 at its rear end to which the rear 100 end of a cutter guard 126 is pivotally connected. The cutter guard 126 consists of a vertical plate 127 at the free end of which a curved cutter guard 128 is fixed. The guard proper 128 is adapted to lie in front of the 105 cutter 53 at the time the operator is placing the slug in the vise, or removing it from the vise to prevent any possibility of the operator's hand coming in contact with the cutter which may be running at this time. 110

When the cutter is operating on a slug, it is lifted to a raised position out of the way because at this time there is no danger and the operator wants a clear view to observe just what he is doing.

The guard is lifted as the vise is swung in toward the cutter by means of a fixed camming pin 129 on the frame of the machine upon which the lower edge 130 of the guard plate 127 rests, and by means of which the 120 guard proper 128 is positioned vertically.

The lower edge 130 has an offset 131 which contacts with the pin 129 and raises the plate 127 and guard 128 as the stop bar 82 is moved into cutting position.

The two positions of the guard are illustrated in Figs. 3 and 4, the lower or guarding position in full lines and the upper position in dotted lines.

The chute 119 is preferably enclosed with- 130

in a box-like structure 132 adapted to be secured to the base of the machine by a screw 133. The box 132 has an open outer end 134 and this is preferably provided with a chip deflector plate 135 adapted to deflect the escaping chips downwardly at the end of the machine where they can readily drop down into a suitable container.

As the stop bar 82 fits into notches in the frame 59 and fine chips or dust might accumulate beneath the bar in the notches, I prefer to limit its rearward movement in the notches by relatively small adjustable stops 136 in the form of small screws arranged in threaded openings in the frame 59 and adapted to contact at their points with the stop bar 82. The possibility of chips or dust getting between the bar and the points of these small screws is quite remote.

It should be understood that the illustrations shown are merely typical of the many uses of the machine in the production of novel arrangements of type slugs.

As many modifications of the invention will readily suggest themselves to one skilled in the art, I do not limit or confine the invention to the specific details of construction or operation herein shown and described.

I claim:

1. In a machine of the kind described, a rotary cutter, a vise mechanism for holding a printing slug for presentation to the cutter, the vise movable from and toward the cutter and the vise mechanism movable longitudinally of the vise at right angles to the plane of the cutter, means for setting the vise in a plurality of relations in reference to the cutter for operation upon a type slug held in the vise to produce a like plurality of results, a cutter guard adapted to drop in front of the cutter at times when the vise is swung away from the cutter and means for automatically raising the guard when the vise is moved toward the cutter for cutting a slug held therein.

2. In a machine of the kind described, a rotary cutter, a vise mechanism for holding a printing slug for presentation to the cutter, the vise movable from and toward the cutter and the vise mechanism movable longitudinally of the vise at right angles to the plane of the cutter, means for setting the vise in a plurality of relations in reference to the cutter for operation upon a type slug held in the vise to produce a like plurality of results, a guard adapted to drop in front of the cutter when the vise is moved away from the cutter and to be raised when the vise is moved toward the cutter, and means operatively connecting the guard with the vise for automatically changing the guard.

3. In a machine of the kind described, a rotary cutter, a guide bar arranged at right angles to the plane of the cutter, a vise mechanism slidably mounted on said bar and mov-

able back and forth past the cutter and also from and toward the cutter, the mechanism including a vise which is pivotally mounted to swing in a vertical plane to set the vise in two positions relative to the cutter, in one of said positions the vise being adapted to set a slug substantially radially of the cutter and in the other position being adapted to set the slug with its bar substantially tangentially to the cutter, and adjustable stop means for regulating said positions.

4. The invention as defined in claim 3, a longitudinal stop bar on the vise mechanism, and a co-operating stop on the machine for regulating the movement of the vise mechanism toward the cutter and guiding it in its longitudinal movement.

5. The invention as defined in claim 3, a longitudinal stop bar on the vise mechanism, and a co-operating stop on the machine for regulating the movement of the vise mechanism toward the cutter and guiding it in its longitudinal movement, and means at the conveniently positioned means whereby said co-operating stop is readily adjusted to regulate the successive cuts.

6. In a machine of the kind described, a rotary cutter, a vise mechanism movable from and toward the cutter and at right angles to the plane thereof, a longitudinal bar on the vise mechanism below the cutter, a chip chute below the cutter, and means yieldingly holding the chip chute in contact with the bar whereby the chip chute follows the movement of the vise from and toward the cutter.

7. The invention as defined in claim 6, a cutter guard adapted to drop down in front of the cutter when the vise is moved away from the cutter and to be raised up when the vise is moved toward the cutter, and means connecting the chip chute with the guard for causing said changes of position.

8. The invention as defined in claim 6, the chip chute being curved to direct the chips at substantially right angles to the plane of the cutter and a deflector for directing the chips downwardly as they leave the machine.

In testimony whereof, I have hereunto set my hand this 9th day of October, 1930.

CHARLES L. MOHR.
